VACUUM TUBE

Emile Labin, New York, N. Y., assignor to Federal Telephone and Radio Corporation, Newark, N. J., a corporation of Delaware

Application December 15, 1942, Serial No. 469,055

16 Claims. (Cl. 250—27.5)

1

This invention relates to improvements in vacuum tubes, and more particularly to vacuum tubes of the cavity type, adapted for use at high frequencies.

An object of this invention is to provide a novel improved design for a cavity tube.

Another object of this invention is to provide a high frequency cavity tube, capable of handling high power thermionic emission currents.

Still another object of this invention is to provide a high frequency cavity tube, having large heat-dissipating surfaces integral with the electrode elements.

A further object of this invention is to provide a vacuum tube in which the electrodes are formed as integral extensions about the periphery of a resonant cavity, and cooperate with other walls of the cavity in constituting the perimeter.

In general, the invention relates to a cavity tube in which the tube electrodes are built about the cavity resonator, in contrast to usual types of cavity tubes in which the resonator is built about the tube electrodes.

Other objects and advantages of the present invention will appear from the following description of a preferred embodiment and a modification of my novel tube, illustrated in the accompanying drawing, in which:

Fig. 1 is a vertical cross-sectional view of a preferred form of tube construction; and

Fig. 2 is a partial cross-sectional view illustrating a modified structural detail.

While various forms of cavity tubes have been heretofore proposed, all of such known tubes are so designed that the resonator structure is built about the tube elements; in other words, the idea has been to start with a vacuum tube and add the necessary resonator structure to it. This conception of building a cavity tube has resulted in structural limitations, both with respect to the tube elements and with respect to the resonator structure, which seriously interferes with the application of such types of tubes to ultra-high frequency work. The present invention is a radical departure from previously proposed constructions in that I have made the resonant cavity the central part of the tube and have built the tube elements about the cavity. This arrangement provides greater freedom and choice in design and permits the use of the optimum thermionic and electronic relationships.

In Fig. 1 of the attached drawing, there is illustrated an example of a type of cavity tube formed in accordance with the present invention,

2

Two equally dimensioned circular metal plates 10 and 12 are spaced apart parallel to one another by suitable means such as quartz spacing insulators 14, which also provide the cavity with the necessary strength to withstand atmospheric pressure, when the resonator is evacuated. The insulators 14 are preferably located along the locus of voltage minimum points, which can be previously determined. In the form of invention illustrated, the upper plate 10 is provided with a thin ring-shaped metal member 16, attached to the plate and having its outer periphery extending substantially about the outer periphery of the plate. The lower plate 12 is provided with an upstanding ring 18, rigidly attached thereto with its outer periphery at about the periphery of the lower plate. A suitable annular grid structure 20 is attached to the upper edge of the ring 18, so that it is radially spaced from the periphery of the ring 16, by a desired amount. The plates 10 and 12 and the inner surface of the rings 16 and 18 form the resonant cavity for the vacuum tube. About the grid 20 is positioned a ring-shaped cathode 22, which may be indirectly heated as by heater coils 24. The cathode 22 is provided with a radial extension 26 which may be supported by the spacers 14 for positioning the cathode relatively to the grid. A thin disk 28, open at its center is also positioned about the grid 20 and is spaced a short distance from the radial extension 26 on the cathode, the extension 26 and the disk 28 forming between them a capacitative coupling. The electrodes and the resonant cavity may be enclosed by a suitable glass seal 30, connected at one end to the angular knife edge 32, attached to the top of the plate 10, and on the other hand to the annular knife edge 34 attached to the bottom of the plate 12. The disk 28 is preferably of such diameter that it extends through the seal 30, outside of the tube. The heating coil supporting leads 35 will also extend through seal 30 at 37. On the bottom of the plate 12 is provided an annular rim 36, while the under side of the disk 28 outside of the tube periphery is also provided with a depending annular rim 38. An open toroid 40 is set to slidably engage the depending portions of the rims 36 and 38. The toroid 40 thus forms a second external cavity coupling the grid 20, through the lower plate 12, to the cathode 22 through the disk 28 capacitatively coupled with the radial extension 26. By sliding the toroid 40 on the depending rims, the size of the external resonant cavity can be varied as desired. Coupling to the second res-

onant cavity can be effected in any well-known manner, if desired.

In order that the main resonant cavity may be tuned, the lower plate 12 may be provided with a centrally disposed opening covered by a flexible diaphragm 42. A cover 44 over the diaphragm will support a threaded rod 46 connected to the center of the flexible diaphragm, thus varying the size of the internal resonant cavity.

An adjustable coupling to the internal resonant cavity may be provided by the rod 48, extending into the same through a suitable opening in the upper plate 10. For this purpose, the upper surface of the plate 10 may be provided with a threaded bushing 50, positioned about the opening, the bushing supporting in turn a threaded collar 52. The collar 52 slides in an annular groove formed in the extension 53 of a flexible bellows 56, positioned about the opening. A glass seal 54 is connected about a knife edge on the extension 53 and supports the rod 48. It will be obvious that rotation of the collar 52 of the bushing 50 moves the rod 48 in and out of the cavity, to a limited extent, while the flexible bellows 56 maintains an air-tight fit. The upper surface of the plate 10 may also be provided with an up-standing ring 58 supporting a metal cylinder 60, which may serve as a plate line.

A second arrangement which is in most respects similar to that illustrated in Fig. 1 is shown in Fig. 2. In this case, however, the electrode surfaces are mounted parallel to the plates instead of at right angles thereto. The ring 116 depending from within the plate 10 is provided with a radial rim, serving as the active anode surface, while a grid 120 is supported at the upper end of the ring 118, so that it is parallel to the radial rim of the anode. The cathode 122 may be constructed similarly as in Fig. 1, but in this case it will be positioned below the grid 120. The cathode may be supplied with the usual heating coil 124 and also has a radial extension 126 spaced from and parallel to the radial disk 128. The heater coils 124 may be supported from the spacers 14 by suitable heater leads 135.

While I have illustrated by way of example, only one modification of the cavity tube structure illustrated in Fig. 1, it is contemplated that in the broad aspects of the present invention many modifications will occur to those skilled in this art. For example, while the plates 10 and 12 have been illustrated as substantially circular, and while such a configuration, having no sharp corners is generally to be preferred, the invention is applicable for use in connection with plates of any desired shape. While the plates have been shown as flat, they also could be curved, provided that in any event each point on one plate is at the same distance from the corresponding point on the other plate as measured along a line normal to the surface at these points. While the tube has been illustrated as of the triode type, it is also contemplated that one of the depending rims forming the outer periphery of the resonant cavity could be used as a cathode electrode, in which case the tube could be a diode. The principles of the invention are, therefore, equally applicable to diodes as well as triodes. Other modifications, particularly in details of construction, will be fairly obvious to those skilled in the art and it is contemplated that such modifications form part of the present invention provided that in all cases, the principle of constructing the vacuum tube elements about the periphery of a cavity resonator is retained. The description of specific ap-

paratus, is therefore, made only by way of example and not as a limitation on the scope of my invention as set forth in the objects and the accompanying claims.

What I claim is:

1. A cavity resonator electron tube including a pair of spaced-apart metal plates, each point on one plate being at substantially the same distance from the corresponding point on the other plate, as measured along a line normal to the surface at these points, an anode electrode electrically connected to and positioned about the periphery of one of said plates, a second electrode connected to and positioned about the periphery of the other plate and spaced from the anode, said electrodes and said plates forming the perimeter of a cavity resonator, and sealing means enclosing said electrodes, closing the space between the two plates.

2. The combination according to claim 1, in which said second electrode is a grid, in combination with a cathode electrode positioned exteriorly of and on that side of the grid opposite the anode.

3. The combination according to claim 1, in which said plates are flat parallel plates and said electrodes are formed as oppositely inwardly directed rings extended about the peripheral edges of said plates.

4. A cavity resonator electron tube including, a pair of spaced-apart flat parallel plates forming part of the perimeter of the tube, an anode electrode electrically connected to and positioned about the peripheral edge of one of said plates, a grid electrode connected to and positioned about the peripheral edge of the other plate and spaced from the anode, said plates and said electrodes forming the perimeter of a cavity resonator, a cathode electrode positioned on that side of the grid opposite the anode, and sealing means enclosing said electrodes between the plates.

5. The combination according to claim 4, in which said plates are circular and said anode and grid electrodes are formed as rings inwardly directed toward one another.

6. A cavity resonator electron tube comprising, a pair of flat circular metal plates, insulating spacing means between said plates positioning them parallel with one another, a thin metal ring connected to the periphery of one of said plates forming anode electrode, a second thin metal ring connected to the periphery of the other plate, an annular grid supported by the second ring in spaced relationship with the first ring, said plates and said rings defining the perimeter of a cavity resonator, an annular cathode mounted at the side of the grid opposite the anode, and sealing means enclosing said electrodes and connected to the two plates.

7. The combination according to claim 6, in which said cathode has an outwardly directed radial extension, in combination with a thin metal ring having a lateral face parallel to and spaced from said extension, said ring extending through and supported by said sealing means, and forming a terminal capacitatively coupled with said cathode.

8. The combination according to claim 6, in which said cathode has an outwardly directed radial extension, in combination with a thin metal ring having a lateral face parallel to and spaced from said extension, said ring extending through and supported by said sealing means, and forming a terminal capacitatively coupled with said cathode, and means outside of said cavity resonator and outside of said sealing means, forming a second cavity resonator between the

grid-supporting plate and said parallel metal ring.

9. The combination according to claim 6, in which said cathode has an outwardly directed radial extension, in combination with a thin metal ring having a lateral face parallel to and spaced from said extension, said ring extending through and supported by said sealing means, and forming a terminal capacitatively coupled with said cathode, a rim depending from said parallel ring outside of said sealing means, a second rim depending from the outer surface of the grid-supporting plate in the same direction as the first rim, and a toroid having an open lateral face engaging the two dependent rims, and forming with them a second and external cavity resonator coupling the grid to the cathode through said capacitating coupling.

10. The combination according to claim 6, in which the grid-supporting plate has a substantially central hollow opening, in combination with a flexible diaphragm covering this opening and sealed at its edges to the plate, means operatively connected with said diaphragm for moving it to tune the resonator, and resonator coupling means supported by and extending through the other plate.

11. The combination according to claim 6, in which said cathode has an outwardly directed radial extension, in combination with a thin metal ring having a lateral face parallel to and spaced from said extension, said ring extending through and supported by said sealing means forming terminal capacitatively coupled with said cathode, a rim depending from said parallel ring outside of said sealing means, a second rim depending from the outer surface of the grid-supporting plate in the same direction as the first rim, and a toroid having an open lateral face adjustably, slidably, engaging the two depending rims, and forming with them a second and external cavity resonator coupling the grid to the cathode through said capacitative coupling.

12. The combination according to claim 6, in which said rings are both mounted at right angles, to and between the metal plates, in which said grid surrounds the first metal ring, and in which said cathode surrounds the grid.

13. The combination according to claim 6, in which the first metal ring is inwardly directed toward the other plate and is provided at its outer end with an outward radial extension interme-

diate and substantially parallel to the two plates, in which said second metal ring is inwardly directed toward the other plate, and in which said grid is connected to the outer end of said second ring and extends radially parallel to the radial extension on the first ring.

14. A cavity resonator tube comprising in combination, a pair of flat circular metal plates, insulating spacing means between said plates positioning them parallel with one another, a thin metal ring connected about the periphery of one of said plates, inwardly directed toward the other plate and provided at its outer end with an outward radial extension intermediate and substantially parallel to the two plates to form an anode electrode, a second thin metal ring connected about the periphery of the other plate, inwardly directed toward the first plate, said plates and said rings defining the perimeters of a cavity resonator, a grid connecting to the other end of said second ring and extending radially, parallel to the radial extension on the first ring, an annular cathode mounted about the side of the ring opposite the anode, said cathode being formed with an outwardly directed radial extension, sealing means enclosing said electrodes and connected between the two plates, a thin metal ring having a lateral face parallel to and spaced from said extension, said last ring extending through and supported by said sealing means to form a terminal capacitatively coupled with said cathode, and means outside of said cavity resonator and outside of said sealing means forming a second cavity resonator between the grid-supporting plate and said parallel metal ring.

15. The combination according to claim 14, in which said second cavity resonator forming means comprising a rim depending from said parallel rim outside of said sealing means, a second rim depending from the outer surface of the grid supporting plate in the same direction as the first rim, and a toroid having an open lateral face engaging the two depending rims.

16. A cavity resonator electron tube including, a pair of spaced-apart metal plates, a pair of spaced electrodes respectively mounted on and about the outer periphery of said plates to form with said plates the perimeter of a cavity resonator, and sealing means connected between said plates and enclosing said electrodes.

EMILE LABIN.
